UNITED STATES PATENT OFFICE.

FRANCIS M. LINDERSMITH, OF SPOKANE, WASHINGTON.

WINDOW.

Application filed August 6, 1927. Serial No. 211,196.

My present invention relates to improvements in windows and particularly to the frame structure and the means for securing the glass panel in the sash. While I have 5 hereinafter referred to the invention as embodied in a window, it will be understood that my invention is capable of being embodied in door and other constructions where a glass or similar panel is utilized, 10 and I therefore do not limit the invention to its use in a window.

By the employment of my invention in the window construction the necessity for use of putty in the glazing operation is 15 dispensed with and of course puttying in the process of repairs is also avoided. An airtight and weather tight joint is secured between the wood bars of the window and the glass panel and rattlings of the panel 20 in its seat in the wood bars is eliminated, while at the same time an adequate seal is secured that prevents breaking or cracking of the glass panel edges in the bars of the window.

25 In the accompanying drawings I have illustrated one complete example of the physical embodiment of my invention, together with slight modifications, wherein the combinations and arrangements of parts of the 30 window are shown, constructed according to the best modes I have thus far devised for the practical application of the principles of my invention.

Figure 1 is a perspective view of a window 35 sash constructed according to my invention, which may be the lower or upper sash of a double window construction.

40 Figure 2 is a perspective view of the sash of Figure 1 with the upper cross bar or rail, and glass panel separated from the remaining parts of the window, as in the course of constructing the window.

Figure 3 is a transverse horizontal sectional view at line 3-3 of Figure 1.

45 Figure 4 is an enlarged detail sectional view showing an undercut groove in one of the frame bars for the edge of the glass panel.

50 Figure 5 is a sectional detail view showing another form of undercut groove in the frame bar, and a sealing cement or similar composition embedded within the undercut

groove and about the edge of the glass panel.

In the form of my invention exemplified 55 in the drawings the window is provided with the two side stiles 1 and 2, the bottom transverse or cross bar 3 with mortised ends 4, and the top bar or rail 5 also has mortised ends 6. The rectangular glass panel is indicated by the letter G throughout the figures of the drawing and this panel is first secured in the side rails or stiles 1 and 2 and pushed down by the use of the top rail 5 as indicated in Figure 2. The upper ends 60 of the side stiles are fashioned with tenons 7 that fit within the mortises 6 of the top rail 5. All of the bars or rails forming the square or rectangular frame are fashioned with grooves 8 in which the edges of the glass panel G are fitted.

70 The upper sash bar or rail 5 is secured at its ends to the tops of the side stiles by means of dowel pins 9 that are secured in dowel holes 10 in the mortised and tenoned ends of the sash bars, and the sash frame is 75 thus retained together in rigid corner joints. The usual grooves 11 are provided in the sides or outer faces of the side stiles for the sash cords and the stiles, top rail and bottom bar are provided with usual or desired mold 80 or trim.

85 In Figure 4 one of the sash bars as 12 is shown with an undercut groove 13 for the edge of the glass panel G and the groove is fashioned of such a size as to necessitate forcing the edges of the panel into the groove thus slightly spreading the clamp beads 14 at the opposite sides of the panel. The wood of course possesses the required 90 elasticity or resiliency to permit a slight spreading or separating of the two beads and they are clamped with frictional contact against the opposite sides of the glass panel G to form a weathertight seal with a cushioned pressure on the glass that avoids breakage or 95 cracking of the glass.

100 In Figure 5 the sash bar 15 has an undercut groove 16 and a plastic cement 17 or other similar plastic material is injected into the undercut groove to form a filler around the edges of the glass panel and thus provide a weather tight seal as well as an anti-rattling feature for the glass in its sash frame.

If necessary or desirable, the dowel pins may be removed to permit separation of the top rail from the remainder of the frame, and a glass panel may be substituted for the original, after which the parts are again assembled and the dowel pins pressed into place.

Having thus fully described my invention what I claim as new and desire to secure by Letters Patent is—

In a sash frame the combination with an

integral frame member and its glass panel, said member having an undercut groove for the panel with the opening of said groove of less width than the thickness of the glass panel whereby resilient beads are formed at the opposite sides of the panel, and a plastic filter encased within said groove at the edge of the panel.

In testimony whereof I affix my signature.

FRANCIS M. LINDERSMITH.
